UNITED STATES PATENT OFFICE.

CHARLES J. KATCHEM, OF MINNEAPOLIS, MINNESOTA, ASSIGNOR OF ONE-HALF TO
SAMUEL GOTTLIEB, OF MINNEAPOLIS, MINNESOTA.

STEAM-TRAP.

1,293,111.

Specification of Letters Patent.

Patented Feb. 4, 1919.

Application filed April 19, 1917. Serial No. 163,155.

To all whom it may concern:

Be it known that I, CHARLES J. KATCHEM, a citizen of the United States, residing at Minneapolis, in the county of Hennepin 5 and State of Minnesota, have invented certain new and useful Improvements in Steam-Traps, and I do hereby declare the following to be a full, clear, and exact description of the invention, such as will enable others skilled in the art to which it appertains to make and use the same.

My invention relates to what is generally known as vacuum valves, and which devices are used in connection with the radiators of steam heating systems having a return pipe connected to a vacuum pump or other means for maintaining partial vacuum in the heating system. Generally stated, the invention consists of the novel 15 devices and combinations of devices hereinafter described and defined in the claims. In these so-called vacuum valves, there is a condensing chamber arranged to maintain a water seal which will prevent the 20 escape of steam to any considerable extent from the radiator to the return pipe; and there is a float actuated valve combined with certain ports for maintaining a nearly constant amount of water in the condensing 25 chamber and for regulating or controlling the action of the partial vacuum in the return pipe in its tendency to draw steam into the radiator.

In the accompanying drawings which 30 illustrate the invention, like characters indicate like parts throughout the several views.

Referring to the drawings:

Figure 1 is a vertical section with some parts in full, showing the improved valve 35 mechanism; and

Fig. 2 is a horizontal section on the line 2-2 of Fig. 1.

The condensing chamber of the valve mechanism is preferably formed with trans- 40 parent walls and, as shown, is made up of a heavy glass cylinder 3, a lower head 4 and an upper head 5, said heads having countersunk gaskets 6 for making steam-tight joints between the said body and head.

45 The numeral 7 indicates the steam pipe that leads from the upper portion of the radiator through the bottom of the lower head 4 at a point eccentric to its axis, and the numeral 8 indicates a steam return pipe 50 which leads axially through said head 4

and back to the boiler. In large steam heating plants this return pipe 8 would be connected to a vacuum pump. A tubular stem 9 is tapped into the upper end of the return pipe 8, extends axially upward 60 through the cylinder 3 and through the upper head 5, and forms a steam-tight joint with the said head 5 being, as shown, provided with a nut 10 on top of said head.

65 A float 11 is mounted to slide vertically on the stem 9 and this float has a tubular axial sleeve 12 that works freely, but with close engagement, with the exterior of the said tubular stem. Normally, the lower 70 end of the sleeve 12 rests on a shoulder 13 of the tubular stem 9 and closes radial ports 14 formed in the lower portion of said tubular stem a considerable distance above the bottom thereof. In the upper 75 portion of the tubular stem 9 are vertically spaced perforations 15 that preferably are progressively larger in an upward direction.

Working with threaded engagement in 80 the upper portion of the axial passage of the tubular stem 9 is the choke valve in the form of a threaded stem 16 shown as provided with a knurled head by means of which it may be readily rotated. By ad- 85 justments of the valve 16, more or less of the perforations 15 may be opened. It is, of course, understood that a partial vacuum will be maintained in the return pipe 8 from the pump, not shown, but referred to 90 above, and it, therefore, follows, that with a predetermined partial vacuum maintained in the said return pipe, the amount of steam that will be drawn to the radiator will depend on the number of perforations 15 95 opened up. The choke valve 16, therefore, affords means for regulating the amount of steam that will be drawn to the radiator.

100 When there is no water in the radiator and steam is first turned on, the float 11 and sleeve valve will be in their lowermost positions, as above stated, and all of the ports 15 not closed by the choke valve 16 will then be opened. The partial 105 vacuum from the return pipe 8 will then be effective to draw or facilitate the flow of steam into the radiator. This action, as stated, may be regulated by adjustments of the said choke valve 16.

110

When water condenses in the radiator, it will find its common level in the condensing chamber until it reaches a point somewhat above the dotted line 2-2 of Fig. 1, but 5 will then raise the float 11 and sleeve valve 12 causing the latter to uncover drain ports 14. In this way, whenever the level of the water in the condensing chamber slightly exceeds the altitude of the ports 10 14, said ports will be opened and the condensing chamber will be drained down to the level of the said ports, but not lower, because the float in the sleeve valve 12 immediately lowers and causes the same to 15 inclose the said ports 14 and, moreover, the said condensing chamber cannot possibly be drained into the return pipe lower than the said ports. The only way that the condensing chamber can be drained to a 20 point below ports 14 is for the water to run back from the radiator through the steam supply pipe.

When the float and sleeve valve are raised, the upper end of the latter will close more or 25 less of the air ports 15, thereby either cutting off or decreasing the action of the partial vacuum in drawing steam into the radiator.

Overlying the delivery end of the pipe 7 30 is an inverted U-shaped deflecting plate 18 which is secured to the lower head 4. This deflecting plate prevents steam, when the condensing chamber is dry, from striking directly against the float and when water is 35 in the condensing chamber, prevents the direct upward flow of water against the said float so that the action of the float is not influenced by the impact of incoming steam or of inflowing water.

40 The transparent walls of the condensing chamber permit the action of the float and controlling valve and the altitude of water in the condensing chamber, readily to be observed; but in some forms of the device it 45 may be further advisable to substitute a metallic or other opaque shell in lieu of the glass cylinder 3.

What I claim is:

1. In a device of the kind described, the 50 combination with a condensing chamber having two pipe connections, one for connecting to a radiator, and the other serving as a return tube, of a tubular stem extending from said return pipe upward into said condensing chamber and provided with upper and lower lateral ports, a sleeve valve working on said tubular stem and normally closing the lower ports thereof, a float connected to said sleeve valve, and serving when raised 55 to cause said sleeve valve to open said lower ports, and a choke valve in the upper end of said tubular stem for opening and closing the upper ports of said stem.

2. In a device of the kind described, the 60 combination with a condensing chamber

having two pipe connections, one for connecting to a radiator, and the other serving as a return tube, both of said pipes opening through the bottom of said chamber, of a tubular stem extending from said return 70 pipe upward into said condensing chamber and provided with upper and lower lateral ports, a sleeve valve working on said tubular stem and normally closing the lower ports thereof, a float connected to said sleeve 75 valve, and serving when raised to cause said sleeve valve to open said lower ports, the ports in the upper portion of said tubular stem being longitudinally spaced, and a choke valve working in the upper end of 80 said tubular stem and adjustable to open or close more or less of the said upper ports.

3. In a device of the kind described, the combination with a condensing chamber having two pipe connections, one for connecting to a radiator, and the other serving 85 as a return tube, both of said pipes opening through the bottom of said chamber, of a tubular stem extending from said return pipe upward into said condensing chamber 90 and provided with upper and lower lateral ports, a sleeve valve working on said tubular stem and normally closing the lower ports thereof, a float connected to said sleeve valve, and serving when raised to cause said 95 sleeve valve to open said lower ports, the ports in the upper portion of said tubular stem being longitudinally spaced, and a choke valve working in the upper end of said tubular stem and adjustable to open or 100 close more or less of the said upper ports, the said choke valve having threaded engagement with said tubular stem and having a finger piece exposed at the exterior of said condensing chamber.

4. In a device of the kind described, the combination with a condensing chamber having two pipe connections, one for connecting to a radiator, and the other serving as a return tube, both of said pipes opening 110 through the bottom of said chamber, of a tubular stem extending from said return pipe upward into said condensing chamber and provided with upper and lower lateral ports, a sleeve valve working on said tubular 115 stem and normally closing the lower ports thereof, a float connected to said sleeve valve, and serving when raised to cause said sleeve valve to open said lower ports, the ports in the upper portion of said tubular stem being longitudinally spaced, and a choke valve working in the upper end of 120 said tubular stem and adjustable to open or close more or less of the said upper ports, the said sleeve valve when raised serving to 125 close more or less of the said upper ports.

5. In a device of the kind described, the combination with a condensing chamber having two pipe connections, one for connecting to a radiator, and the other serving 130

as a return tube, both of said pipes opening through the bottom of said chamber, of a tubular stem extending from said return pipe upward into said condensing chamber 5 and provided with upper and lower lateral ports, a sleeve valve working on said tubular stem and normally closing the lower ports thereof, and a float connected to said sleeve valve, and serving when raised to cause said 10 sleeve valve to open said lower ports, the

said condensing chamber comprising upper and lower metallic heads and an interposed glass tube.

In testimony whereof I affix my signature in presence of two witnesses.

CHARLES J. KATCHEM.
